Primary Examiner — Steven J Czyz

(57) **CLAIM**

The ornamental design for a base for food processor, as shown and described.

DESCRIPTION

1. Base for food processor

1.1 Front

1.2 Back

1.3 Left

1.4 Right

1.5 Top

1.6 Bottom

1.7 Perspective

The broken lines shown in reproductions 1.5 and 1.7 depict portion of the base for food processor form no part of the claimed design.
